UNITED STATES PATENT OFFICE.

HARRY H. SCHROYER, OF CHICAGO, ILLINOIS, ASSIGNOR TO DUNBAR MANUFACTURING COMPANY, A CORPORATION OF ILLINOIS.

TELESCOPING METAL CAR-DIAPHRAGM.

1,256,054.

Specification of Letters Patent. Patented Feb. 12, 1918.

Application filed March 25, 1916. Serial No. 86,617.

To all whom it may concern:

Be it known that I, HARRY H. SCHROYER, a citizen of the United States, and a resident of the city of Chicago, in the county of Cook 5 and State of Illinois, have invented certain new and useful Improvements in Telescoping Metal Car-Diaphragms; and I do hereby declare that the following is a full, clear, and exact description of the same, reference 10 being had to the accompanying drawings, and to the numerals of reference marked thereon, which form a part of this specification.

This invention relates to an improved 15 type of car diaphragm wherein the parts are constructed of metal and adapted to telescope with one another. Many different types of metal car diaphragms have been constructed heretofore, but in many instances the same have proved objectionable, 20 due to the imperfect seal afforded between the parts as well as the noisy operation of the diaphragm when in use. This invention, however, relates to an improved type 25 of metal car diaphragm wherein the parts interfit to permit expansion and contraction of the diaphragm according to conditions imposed thereon, and with the parts sealingly connected to afford a weatherproof 30 construction and so associated as to permit the adjustments of the diaphragm to take place necessitated by relative movement occurring between coupled cars on which the diaphragms are mounted and connected to 35 one another.

It is an object therefore of this invention to construct a telescoping metal car diaphragm wherein the top and side wall members of the movable sections of the diaphragm are adjustably connected to permit 40 relative movement therebetween and furthermore with the face plate adjustably connected to said top and side wall portions of the movable diaphragm section to permit 45 adjusting movements of the face plate, all of the parts coöperating to permit adjustments of the diaphragm in practically any direction.

It is also an object of this invention to 50 construct a telescoping metal car diaphragm wherein the top and side wall members are adjustably and sealingly connected to one another to permit adjusting movements thereof due to the weaving effect imposed

upon the diaphragm when in use, and further with a sealing means mounted upon the car body coacting with movable portions of the diaphragm to effect a seal therearound.

It is furthermore an important object of this invention to construct a metal car diaphragm wherein the face plate is adjustably mounted upon the forward end of the movable section of the diaphragm in a manner to efficiently support the same, and with the side walls of the movable section of the diaphragm adjustably connected to the top wall thereof so that adjusting movements of the face plate to which the top wall is connected and supported thereby, may easily take place.

It is finally an object of this invention to construct an improved type of metal car diaphragm with the parts so associated as to permit adjusting movements of the parts of the diaphragm to care for any conditions 75 of operation, and acting efficiently to perform the purpose.

The invention (in a preferred form) is illustrated in the drawings and hereinafter more fully described.

In the drawings:

Figure 1 is a central vertical section with parts shown in elevation, taken through the upper end of a diaphragm embodying the principles of my invention.

Fig. 2 is a fragmentary top plan view thereof with parts shown in elevation and parts in section.

Fig. 3 is a fragmentary detail section taken on line 3—3 of Fig. 1, with parts 90 omitted and parts shown in section.

Fig. 4 is a detail section taken on line 4—4 of Fig. 3.

Fig. 5 is a detail section taken on line 5—5 of Fig. 3.

Fig. 6 is a detail section taken on line 6—6 of Fig. 4 with parts omitted and parts in elevation.

Fig. 7 is a fragmentary detail section taken on line 7—7 of Fig. 1.

Fig. 8 is a fragmentary detail section taken on line 8—8 of Fig. 1 with a portion of the structure shown in elevation.

Fig. 9 is an enlarged sectional detail illustrating the connection of the elements at one 105 side of the mechanism, as shown in Fig. 7.

Fig. 10 is an enlarged detail section of part of the mechanisms shown in Fig. 9.

As shown in the drawings:

The body of the car, which may be of any conventional type, is denoted as a whole by the reference numeral 1, and secured thereto and extending inwardly from the end of the car and projecting slightly beyond the end thereof is a plate 2, bent to an acute angle or gable shape, as shown in Fig. 8. Also secured rigidly to the car body in 5 any suitable manner and forming a part thereof, is a vertical plate 3, to which the rear or inner end of the plate 2, which is flanged outwardly for the purpose, is secured in any suitable manner. A rigid horizontal partition or plate 4, extends transversely across the upper end of the car body upon which the lower flanged margin of the upright plate 3, is secured in any suitable manner. Mounted within the compartment 10 afforded by the gable shaped top plate 2, and bottom plate 4, and upright plate 3, is a compartment member having double top walls 5 and 6, respectively, secured to one another at their forward flanged ends and 15 angled in gabled relation parallel to the top wall member 2, and a bottom wall 7, forming a part of said compartment member is also provided, as clearly shown in Fig. 1. Extending slidably through said 20 compartment and rigidly held in the vertical rear wall 3, is a buffer rod 8, around which a coiled compression spring 9, is disposed, bearing at one end against said wall 3, and at its other end against the forward 25 end of an extensible section of the diaphragm hereinafter described. The movable or telescoping section of the diaphragm is adjustably connected to the face plate of the diaphragm, which is denoted by the 30 reference numeral 10. Said movable diaphragm section consists of an acute angled or gabled top wall 11, the forward margin 12, of which is riveted to the rear surface of the face plate 10, and the lower or outer 35 margins of which are turned horizontally inwardly as denoted by the reference numerals 13. The side walls of the movable diaphragm section are denoted by the reference numerals 14, and the upper margins 40 thereof are turned inwardly and hooked upwardly, as denoted by the reference numeral 15, to receive the inturned margins 13, of the top wall bearing thereupon, and said top wall margins 13, are provided with a strip 45 of sealing material 16, which is interposed between the metal marginal portion 13, and the margin 15, of said side walls. Each of the forward vertical margins of the side wall are beaded outwardly, as denoted by 50 the reference numeral 17, and fits beneath an inwardly turned retaining strip 18, which, together with a flat bearing strip or wear plate 19, for the beaded end 17, of said side walls, is secured upon the inner or rear 55 surface of the face plate 10.

Said beaded ends of the retaining strip or plate 18, are cut away at points in the length thereof, and secured in any suitable manner within the beaded portion of the side walls 14, are blocks 20, which fit into the cut away portions, so that the side walls 14, are supported vertically upon the face plate 10, and yet the face plate is capable of adjustment with respect thereto.

Said side walls 14, are adapted to telescope within and between vertically disposed side walls 21 and 22, mounted in upright position in the end of the car, the forward ends of said respective side walls flanged outwardly and the forward end of 75 the compartment therebetween provided with sealing means 23, mounted on insert plates 24, between which said side walls 14, sealingly extend. The rear margins of the side wall members 21, are flanged over, as 80 denoted by the reference numeral 25, and bent into parallel relation with the side wall members 22, and beaded over, as denoted by the reference numerals 26, and fit beneath beaded sealing strips 27, which, together 85 with wear plates 28, are secured upon the rear surface of an I-beam 29, forming a part of the car body. Said compartment side wall members 21 and 22, are adjustably associated with the car frame to permit a 90 slight weaving or horizontal swinging movement thereof to take place.

Hingedly mounted in inclined position on the front of the car end above the top wall member 11, are plates 30, the lower ends of 100 which are provided with a sealing strip 31, and springs 32, are mounted to impel said plates 30, downwardly upon the respective inclined surfaces of said top wall 11, to seal the same and prevent entrance of water, cinders, snow, dust, and the like, over the inner rear end of said gable top member 11.

As clearly shown in Fig. 1, the forward end of the slideable buffer rod 8, is secured by means of a pin 33, into lug extensions 34, 110 provided on the inner rear surface of the face plate 10.

The operation is as follows:

The outer wall sections 14, and top wall members 11, of the movable diaphragm section are adapted to move inwardly of the car end, the side walls 14, telescoping within the respective side walls 21 and 22, which are adjustably mounted in the end of the car so as to be capable of a slight lateral movement, and the top wall member moving between the interior gable top wall member 2, and the gable wall member 5, beneath the sealing means 31, which is slideable thereon. The top wall 11, is not only of gable shape, 115 but converges rearwardly from the face plate 10, inwardly to its rear margin, as clearly shown in the partial plan view of Fig. 2, so that the top wall member is capable of a 120 swinging movement rigid with the face 125 130

plate 10, when such movements are imposed thereupon without possibility of the top wall member 11, striking the sides of the compartment provided therefor. As pointed out, the gable top wall member 11, of the movable diaphragm section is sealed by the hinged plates 30, provided with sealing means 31, bearing thereon, and the side wall members 14, of said movable diaphragm section are sealed due to the fact that the same slide between the sealing means 23, provided therefor between the walls 21 and 22, into which said side wall members telescope when moved inwardly.

I am aware that various details of construction may be varied through a wide range without departing from the principles of this invention, and I therefore do not purpose limiting the patent granted otherwise than necessitated by the prior art.

I claim as my invention:

1. A metal car diaphragm of the class described comprising compartment sections adjustably mounted upon the car body, side wall members of a movable section adapted to telescope therewith, a face plate secured on the forward end of said side wall members, a gabled top wall rigidly secured to said face plate and adjustably associated with the upper margins of said side walls, and sealing means to seal against the top and side wall members in all telescoping adjustments thereof with reference to the car.

2. In a diaphragm construction of the class described, the combination with a car, of compartment side wall members adjustably mounted thereon, a top wall member rigidly mounted over said side wall members, a telescoping section comprising side walls to telescope within said compartment members, a top wall member adjustably associated with said side walls adapted to move inwardly beneath the aforesaid top wall member within a car, means associated with said compartment side wall members to seal against said side walls of the movable diaphragm section, and means sealing against the top wall member of said movable diaphragm section.

3. In a diaphragm construction of the class described, telescoping diaphragm sections, certain thereof provided with sealing means to seal the telescoping sections, auxiliary sealing means bearing upon the exterior of certain of the other portions of one of the diaphragm sections, a face plate adjustably connected to the side walls and rigidly to the top wall of one of the diaphragm sections, and an adjustable connection between one of the diaphragm sections and the car body on which the diaphragm is mounted.

4. A diaphragm of the class described comprising compartment side walls adjustably connected to the car, a rigid top wall therefor, movable sections comprising side

walls interfitting said compartment side walls, a top wall therefor adjustably associated therewith, a face plate for said movable diaphragm section adjustably connected to the forward ends of said side walls and rigidly to said top wall, and sealing means to seal said top wall and side walls of the movable diaphragm section in all positions of adjustment thereof.

5. A car diaphragm of the class described comprising stationary and movable sections, said stationary section comprising compartment members, said movable section comprising members adapted to interfit slidably within said compartment members, insert plates for the compartment member, a sealing member secured to each plate between which the movable section extends, sealing the connection between said respective stationary and movable sections in all positions of adjustment thereof.

6. A diaphragm comprising stationary and movable sections interfitting one another, one thereof embracing a top wall member adjustably associated with side wall members, the other embracing compartment side wall members, and a roof member rigidly associated therewith, sealing means on said compartment side wall members adapted to seal against the side wall members of the movable section telescoping therewith, and a sealing means between said respective roof member and top wall member of the diaphragm.

7. A car diaphragm of the class described comprising stationary and movable diaphragm sections adapted to telescope with one another, one of said sections comprising side wall members, and a top wall member adjustably associated therewith and capable of transverse movement with respect thereto, sealing means associated with said stationary diaphragm section to seal the movable sections telescoping therewith, and means permitting movement of certain of said members of said stationary diaphragm section with respect to the car on which it is attached.

8. The combination with a car, of a vestibule car diaphragm attached thereon comprising stationary and movable sections adapted to telescope with one another, a roof member forming a part of said movable section capable of transverse relative movement with respect to the stationary section, walls forming a part of said movable section having said roof member adjustably associated therewith, and an adjustable connection between certain of the members of said stationary diaphragm section and the car on which the diaphragm is mounted.

9. The combination with a car, of a vestibule car diaphragm attached thereon comprising stationary and movable sections adapted to telescope with one another, said

stationary section comprising flexibly mounted compartment side walls, a stationary roof member, and said movable section comprising flexibly mounted side walls 5 adapted to telescope within said compartment side walls, a top wall adjustably connected therewith, means sealing over the upper surface of said top wall as the same moves beneath said roof member, and a sealing connection between said compartment side walls and the side walls of the vestibule movable section.

10. A car vestibule diaphragm of the class described, a stationary section comprising a rigid roof member, compartment side walls, a movable section comprising flexibly mounted side walls adapted to telescope within said compartment side walls of the stationary section, a top wall member adapted to move into telescoping relation beneath said roof member, and hingedly mounted spring impelled sealing means adapted to seal along the upper surface of said top wall of the movable diaphragm section to seal the same at the entrance thereof 25

into and beneath said roof member of the stationary section.

11. In a vestibule diaphragm of the class described, a stationary vestibule section, and a movable vestibule section comprising a 30 face plate, side wall members, the forward margins thereof beaded over, a headed hinge member on the face plate engaging said margins affording a hinged connection of the side walls to the face plate, a top wall 35 member rigidly secured to said face plate and of gable shape, a slid able sealing connection between said top wall and said side walls of said movable diaphragm section, and sealing means at the point of connection 40 of said movable diaphragm section with said stationary diaphragm section.

In testimony whereof I have hereunto subscribed my name in the presence of two subscribing witnesses.

HARRY H. SCHROYER.
